UNITED STATES PATENT OFFICE.

JAMES F. JETT, OF CARROLLTON, KENTUCKY, ASSIGNOR OF ONE-HALF TO JOSEPH F. JETT,
OF PEORIA, ILLINOIS.

WHISKY-STILL.

No. 908,465.

Specification of Letters Patent.

Patented Jan. 5, 1909.

Application filed August 27, 1908. Serial No. 332,281.

To all whom it may concern:

Be it known that I, JAMES F. JETT, a citizen of the United States, residing at Carrollton, in the county of Carroll and State of Kentucky, have invented certain new and useful Improvements in Whisky-Stills, of which the following is a specification.

The object of my invention is to provide a spent-beer-vapor still in which the distillation is effected by vapor from the liquid remaining after the alcohol has been removed by distillation which is variously known as spent beer, spent wash, or slop, instead of by boiler steam; and my invention consists in the still and the construction and arrangement hereinafter described and claimed.

In the drawings, Figure 1, is a side elevation of a still embodying my invention, a part of the casing being broken away to show the vapor generating apparatus; Fig. 2, a section on line 2—2 of Fig. 1; Fig. 3, a side elevation with the casing broken away and showing my invention applied as an attachment to a still of the ordinary type; and Fig. 4, a partial front elevation.

The apparatus illustrated consists of a heating chamber which may be applied to or connected with the column of any still of the column type, and which is adapted to receive spent beer from the still and deliver vapor to the column; means for generating vapor from the spent beer whereby the distillation may be effected; and means for agitating the spent beer in the heating chamber to avoid any danger that the solid constituents of the spent beer may adhere to the heating surfaces and interfere with the generations of vapor. The preferred means of generating the vapor consists of a series of steam coils within the heating chamber and a steam jacket embracing the chamber.

1 represents the column of a beer still which may be of any desired type; 2, a heating chamber which may serve as the base of the beer column, as illustrated in Fig. 1, or may be an attachment adjacent to the column, as illustrated in Fig. 3; 3, a steam jacket embracing the heating chamber and provided with steam supply pipe 4 and exhaust pipe 5; 6, steam coils mounted within the heating chamber, each connected with a manifold 7 through which live steam may be exhausted; 9, a drop pipe through which the spent wash passes from the column to the heating chamber; 10, a discharge pipe

for the spent beer, commonly known as the slop blow off; 11, a shaft carrying arms or paddles 12 extending between the coils and adapted to keep the spent beer in agitation; 16, a perforated plate (shown in dotted lines) in the beer column slightly below the intake of the drop pipe 9; 17, a float adapted to actuate a valve at 18 in the slop blow off 10; 19, a drain cock for the drop pipe, and 20, a connection for a drain cock for the slop blow off.

In the modification shown in Fig. 3, the heating chamber is provided with a steam dome 13 from which a vapor pipe 14 leads to the column, and a spent beer supply pipe 15 leads from the column to the bottom of the heating chamber. 21, designates a valve adapted to control the flow of the spent beer from the column to the heating chamber; 22, a float, adapted to actuate a valve at 23 in the slop blow off, and 24 and 25 connections for drain cocks in the drop pipe and blow off pipe.

In commencing operations the heating chamber may be charged with water, if no spent beer is available, but if the start is made with water, the spent beer, as fast as it is produced, takes the place of water. The beer, or material to be distilled, is fed into the upper part of the column and descends over the plates in a thin stream in the usual manner, meeting in its descent a counter current of steam generated in the heating chamber whereby the light alcoholic constituents are separated from the heavier non-alcoholic constituents, the former passing upward and outward through the top of the column to the cooler and condenser, and the latter passing downward. In the form shown in Fig. 1, the upper current of steam prevents the spent beer from passing through the perforated plate 16 and the spent beer accumulates until it reaches the top of pipe 9, after which it overflows into that pipe and passes into the heating chamber below where it is heated to the boiling point thereby generating steam which passes upwardly through the perforated plate 16 to meet the downflow of material to be distilled and to effect its distillation. The spent beer accumulates in the heating chamber and rises to the level of the float in the lower part of the column. When the spent beer reaches the float, the float rises thereby opening the valve in the slop blow

off pipe 10 and permitting the spent beer or slop to pass out through the blow off pipe so long as the float is held in a raised position.

5 In the modification shown in Fig. 3, the operation is identical except that the spent wash accumulates in the bottom of the column until it reaches the top of drop pipe 15, when it overflows into that pipe and 10 passes into the bottom of the heating chamber in which it accumulates until it reaches and lifts float 22 opening the valve in the slop blow off and permitting the slop to escape so long as the level is maintained. The 15 steam generated from the spent beer passes through pipe 14 into the bottom of the column and thence upwardly through the descending current of live beer.

It will be noted that the distillation is 20 effected entirely by vapors generated from the spent beer except when it becomes necessary to commence operation with no spent beer available, in which case the single charge of water is quickly exhausted and its 25 place taken by the spent beer. In no case is the objectionable boiler steam brought into contact with the material to be distilled.

I claim as my invention:

1. The combination, in a still, of a distilling column; provisions for delivering live beer into the upper part of the column; a heating chamber; a series of independent steam coils, within the chamber, adapted to generate vapor from the spent beer; a 30 manifold connected with the coils whereby the steam may be exhausted, and provisions for delivering the vapor into the bottom of the column whereby a descending current of live beer is met by a counter current of 35 vapor generated from the spent beer, substantially as and for the purpose specified.

2. The combination, in a still, of a distilling column; provisions for delivering live beer into the upper part of the column; a 40 heating chamber; a series of independent

steam coils, within the chamber, adapted to generate vapor from the spent beer; a manifold connected with the coils whereby the steam may be exhausted; provisions for delivering the vapor into the bottom of the 50 column whereby a descending current of live beer is met by a counter current of vapor generated from the spent beer, and means for agitating the spent beer in the heating chamber, substantially as and for 55 the purpose specified.

3. The combination, in a still, of a distilling column; provisions for delivering live beer into the upper part of the column; a heating chamber; a series of independent 60 steam coils, within the chamber, adapted to generate vapor from the spent beer; a manifold connected with the coils whereby the steam may be exhausted; provisions for delivering the vapor into the bottom of the 65 column whereby a descending current of live beer is met by a counter current of vapor generated from the spent beer; and a steam jacket inclosing the chamber, substantially as and for the purpose specified. 70

4. The combination, in a still, of a distilling column; provisions for delivering live beer into the upper part of the column; a heating chamber; a series of independent 75 steam coils, within the chamber, adapted to generate vapor from the spent beer; a manifold connected with the coils whereby the steam may be exhausted; provisions for delivering the vapor into the bottom of the column whereby a descending current of 80 live beer is met by a counter current of vapor generated from the spent beer; means for agitating the spent beer in the heating chamber; and a steam jacket inclosing the chamber, substantially as and for the purpose specified. 85
